UNITED STATES PATENT OFFICE.

HUGH L. McGINTY, OF PITTSBURGH, PENNSYLVANIA, ASSIGNOR TO SENGBUSCH SELF-CLOSING INKSTAND COMPANY, OF MILWAUKEE, WISCONSIN, A CORPORATION OF WISCONSIN.

DESIGN FOR A SPONGE CUP OR RECEPTACLE.

Application filed January 5, 1924. Serial No. 8,247. Term of patent 14 years.

To all whom it may concern:

Be it known that I, HUGH L. McGINTY, a citizen of the United States, residing at Pittsburgh, in the county of Allegheny and State of Pennsylvania, have invented a new, original, and ornamental Design for Sponge Cup or Receptacle, of which the following is a specification, reference being had to the accompanying drawing, forming part thereof.

The figure is a perspective view of a sponge cup or receptacle, showing my new design.

I claim:

The ornamental design for a sponge cup or receptacle, as shown.
